UNITED STATES PATENT OFFICE

152,186

DESIGN FOR A SEMIAUTOMATIC TABLE
LIGHTER

Prosper W. Buchhart, Closter, N. J.

Application December 16, 1947, Serial No. 143,167

Term of patent 14 years

(Cl. D48—27)

To all whom it may concern:

Be it known that I, Prosper W. Buchhart, a citizen of Germany, residing at Closter, in the county of Bergen and State of New Jersey, have invented a new, original, and ornamental Design for a Semiautomatic Table Lighter, of which the following is a specification, reference being had therein to the accompanying drawing, forming part thereof, in which

Fig. 1 is a top-plan view of a semiautomatic table lighter, showing my new design.

Fig. 2 is a view in side elevation, while

Fig. 3 is a view in side elevation, taken at right angles to Fig. 2.

The characteristic features of my design reside in the portions shown in full lines.

I claim:

The ornamental design for a semiautomatic table lighter, as shown and described.

PROSPER WM. BUCHHART.
